H. N. Jenkins

ATTORNEY

UNITED STATES PATENT OFFICE.

JOHN M. BURKERT, OF ATLANTA, GEORGIA.

SASH-FASTENING DEVICE.

SPECIFICATION forming part of Letters Patent No. 337,369, dated March 9, 1886.

Application filed December 9, 1885. Serial No. 1-5,197. (No model.)

To all whom it may concern:

Be it known that I, JOHN M. BURKERT, a citizen of the United States, and a resident of Atlanta, county of Fulton, State of Georgia, 5 have invented new and useful Improvements in Sash-Fasteners, of which the following is a full and exact description, reference being had to the accompanying drawings, making part of this specification.

10 This invention relates to that class of sash-fastenings which are usually applied to the meeting-rails of window-sashes.

The invention is adapted to be used either with or without a padlock. It is very simple 15 in construction, contains no springs, and is therefore not liable to get out of order; besides, the parts are so connected with each other and with the window-sashes that when properly fastened and locked they cannot be 20 separated by an unauthorized person without breaking the same.

My invention will be readily understood by referring to the accompanying drawings, whereon Figure 1 is a perspective view of the 25 device as when unfastened. Fig. 2 is a similar view as when fastened. Fig. 3 is a plan or top view of the fastening with an auxiliary plate or keeper and a padlock for securing same. Figs. 4 and 5 are detailed views of parts not 30 clearly shown in either of the above figures.

On the drawings, the letters A, B designate the meeting-rails of a pair of window-sashes. The inner edge of the rail A is recessed to receive the downwardly-projecting wing or lug 35 c of the back plate, D, and the ends of the said back plate as well as the aforesaid lug c are provided with holes for the reception of wood-screws, whereby it is designed to be secured to the meeting-rail.

40 The upper surface of the plate D is provided at or about the center thereof with a conical projection, e, having a perforation in the vertical center of same for the passage of a rivet, f, whereby the fastening-lever E is connected therewith, the said lever being provided at one of its ends with a similar perforation, the lower portion of which is recessed to fit over the conical projection of the plate D. The rivet is inserted from the top of the 45 lever, and its point is riveted into a counter-sink at the under side of the plate D.

One side of the lever E is provided with a projection or hook, h, which is adapted to engage a slot, i, formed in the vertical portion k of a front plate, L, which, like the rear plate, is provided with suitable holes for the reception of a pair of fastening wood-screws, m, m'. To the outer or swinging end of the fastening-lever E is pivotally secured a thumb-catch, P, having a downwardly-projecting portion, q, which is adapted to swing around the front end of the raised portion of the plate L and to clamp the lever E against the side of same, and thus prevent the fastening from being accidentally unloosened.

65 The upper part of the thumb-fastening is provided with a perforation, x, for the engagement of a padlock, as will be hereinafter more fully set forth.

70 The letter R designates an auxiliary plate or keeper, the lower edge of which is provided with a slot, a, of sufficient width to straddle the fastening-lever E and the raised portion of the plate L, and is intended to fit immediately in rear of the thumb-catch P after the latter has been made to engage the aforesaid projection of the plate L. This auxiliary plate or keeper has a perforation, x', in the upper part thereof, at sufficient height to be on a line with the perforation in the thumb-catch, in order that the said parts may be secured by a padlock, as shown at S in Fig. 3.

75 By referring to the aforesaid Fig. 3 it will be seen that the auxiliary plate or keeper is made to almost if not entirely cover the heads 80 of the wood-screws, whereby the front plate is secured to its meeting-rail, which makes it impossible to remove same without first unlocking the padlock. Now, as the screw in the lug of the rear plate is entirely hidden from view, it 85 is clear that the sashes cannot be moved without first removing the padlock from the aforesaid parts, then raising the auxiliary plate or keeper, next turning the thumb-screw, and finally swinging the lever E away from the 90 raised portion of the plate L, so as to withdraw the side hook of the said lever from the slotted portion of the front plate.

Having described my invention, what I claim as new, and desire to secure by Letters 100 Patent, is—

1. In combination with a pivoted lever hav-

ing a side hook, as described, a front plate provided with a projecting flange having a perforation therein to receive the aforesaid hook, substantially as and for the purpose specified.

2. In combination with a pivoted lever having a side hook and thumb-catch, as described, a front plate provided with a projecting flange having a perforation therein to receive the aforesaid hook, the latter adapted to be secured in the perforated flange by the thumb-catch, substantially as described.

3. In combination with a fastening-lever, a plate having a raised portion perforated to receive the hook thereof and an auxiliary plate or keeper provided with a slotted portion for straddling the aforesaid parts, substantially as and for the purpose set forth.

4. In a sash-fastening, the combination of a plate having a lever pivotally connected therewith, said lever provided with a side hook, and a pivoted thumb-catch with a plate having a raised projection perforated to receive the aforesaid hook, and an auxiliary plate or keeper adapted to fit in rear of the thumb-screw, and to be connected therewith by means of a padlock, substantially as described, and for the purpose set forth.

In testimony whereof I affix my signature in presence of two witnesses.

JOHN M. BURKERT.

Witnesses:

JAMES P. WEBB,
ROBT. M. ORMOND.
